UNITED STATES PATENT OFFICE

WILLIAM H. WERNER AND CARL NEUMANN, OF BROOKLYN, NEW YORK

SOOT EXTRACTOR

Application filed June 9, 1930. Serial No. 459,982.

The present invention comprehends the provision of a soot extractor adapted to be associated with a chimney or the like, and constructed to separate soot from the smoke or gases passing through the same.

One of the chief characteristics of the present invention resides in a construction of a device of the above-mentioned character, which not only separates the soot from the smoke and gases passing therethrough, but one which is also operable to return the soot to the chimney or stack when desired.

In carrying out the invention, we employ a soot collecting housing supported above the chimney and open at both ends, and in which is arranged means for separating the soot from the smoke and gases passing therethrough, the housing having valve-controlled communication with the chimney, so that soot collected within the housing can be returned to the chimney as the occasion may require.

An object of importance resides in the novel construction of means employed for loosening the soot from the walls of the housing, when it is desired to return the soot and the like to the chimney.

More specifically stated, the invention comprehends means located within the housing for separating the soot from the smoke or gases passing therethrough, including a normally seated valve which regulates or controls the return of the soot from the housing to the chimney, and which means is adapted to be vibrated within the housing with a view of loosening the soot from said means and also from the walls of the housing when it is desired to return the soot to the chimney.

The nature and advantages of the invention will be better understood when the following detailed description is read in connection with the accompanying drawings, the invention residing in the construction, combination and arrangement of parts as claimed.

In the drawings forming part of this application like numerals of reference indicate similar parts in the several views and wherein:

Figure 1 is a sectional view through the de-

vice forming the subject matter of the present invention and showing how it is associated with a chimney or smoke stack.

Figure 2 is a sectional view on line 2—2 of Figure 1.

Figure 3 is a sectional view on line 3—3 of Figure 1.

Figure 4 is a sectional view on line 4—4 of Figure 1.

Referring to the drawings in detail, 10 indicates a soot collecting housing which is open at both ends, and adapted to be supported above a chimney or smoke stack indicated at 11. It will be noted that the upper and lower portions of this housing 10 are of substantially frusto-conical formation as indicated at 12 and 13 respectively. Depending from the lower end of the housing 10 is a hollow tubular member 14 which is partly received within the chimney or smoke stack 11, while carried by this member 14 at an appropriate point in its length, is an annular flange 15 which reposes upon the upper end of the smoke stack or chimney 11 as illustrated. The housing is supported upon the chimney or smoke stack by suitable rods 16 which are bolted or otherwise suitably secured to the housing at spaced points, the rods including extensions 17 which have their corresponding lower extremities offset and embedded in the chimney 11. The rods 16 project an appreciable distance above the upper end of the housing 10 and support a conical-shaped cap 18.

Arranged within the housing 10 is a novel construction of means for causing the smoke and gases passing therethrough to pursue its circuitous course, whereby the soot, cinders and the like are separated from the smoke and gases, and collected within the housing. This means includes a hollow tubular valve 19 which normally reposes upon the member 14, the latter constituting a seat for the valve as illustrated. Carried by this valve 19 at a point adjacent its upper end is a plurality of radially disposed webs 20 which connect and support a bottomless receptacle 21, constituting a baffle for the smoke and gases passing through the housing as will be readily understood. The receptacle 100

21 includes a conical-shaped top wall 22, and it will be noted upon inspection of Figure 1 that the tubular valve 19 projects an appreciable distance within the receptacle 21. Consequently, in the normal position of the parts, the smoke or gases emitted from the chimney or smoke stack 11 pass through the hollow tubular valve 19 into the baffle-like receptacle 21, striking the conical top wall 22 thereof, and are thereby directed downwardly through the open bottom of the receptacle 21, circulating around this receptacle in finding their way through the open upper end of the housing 10. However before the gases and smoke escape from the housing 10, they strike the frusto-conical wall 12 of the housing, which together with the baffle-like top of receptacle 21 separate the soot, cinders and the like from the smoke and gases passing therethrough. The soot separated from the smoke and gases of course is collected by the housing 10, the major portion of which falls to the bottom of this housing, but some of which clings to the walls thereof including the frusto-conical top wall 12. The soot collected by the housing in the manner above stated, is retained within the housing as long as the valve 19 remains seated, but when the valve is elevated and moved away from its seat 14, communication between the housing 10 and the chimney 11 is established, thereby permitting the soot to return to the chimney as will be readily appreciated. The valve 19 is opened and closed by means to be hereinafter described, which means of course permit the valve to be operated from a remote point.

For this purpose I employ a cable 23 having a portion threaded through an apertured extremity 24 of an arm 25 projecting laterally from the upper end of a tubular member 26, the latter being arranged directly above the cap 18 above referred to. The cable 23 enters the tubular member 26 through an opening 27, and is passed through the tubular member to be connected with the baffle-like receptacle 21 by means of chains 28. It will be noted upon inspection of Figure 1 that the cap 18 is provided with a central opening in the top thereof to receive the curved channel-like portion 29 of the tubular member 26, and which portion is connected with one branch 30 of a bell crank lever, the other branch 31 of which is connected with the tubular member 26. The bell crank lever is fulcrumed as at 32 upon a suitable bracket 33, so that when the cable 23 is pulled upon, the tubular member 26 together with the bell crank lever will be rocked upon the pivot 32, thereby bringing the channel-like portion 29 of the tubular member 26 into engagement with the adjacent portion of the cable, to lift the baffle-like receptacle 21 together with the valve 19. The cable 23 is trained over a suitable guide pulley 34

70 journaled in a suitable bracket 35 supported by the cap 18. Surrounding the tubular member 26 immediately adjacent the cap 18 is a plate 36 of the configuration illustrated in Figure 2, and which plate is employed to cover the openings in the cap 18 to prevent rain water or the like passing therethrough. Projecting from the baffle-like receptacle 21 is a plurality of lugs 37 which contact the walls of the housing 10 to guide the receptacle in its movements within the latter, and of course maintain the valve 19 centered to properly engage its seat 14.

75 As hereinabove stated, the valve 19 and the baffle-like receptacle 21 as a unit are 30 adapted to be vibrated within the housing 10, for the purpose of loosening the soot from the receptacle 21 as well as from the wall of the housing 10 when it is desired to return this soot from the housing to the chimney or 35 stack 11. This unit including the valve 19 and the receptacle 21 is vibrated for this purpose by operating the cable 23, thereby lifting the receptacle 21 into contacting engagement with the top wall 12 of the housing, 40 and subsequently allowing the unit to fall or drop within the housing, until the valve forcibly engages the seat 14. In this manner the soot can be effectively loosened from the top wall 12 of the housing as well as 45 from the interior of the receptacle 21 and the walls of the valve 19.

50 For the purpose of loosening the soot collected in the bottom frusto-conical portion 13 of the housing, I employ a plurality of 100 chains 38, the latter having corresponding upper extremities connected with radially disposed arms 39 projecting from the valve 19 at appropriate points in its length, while the corresponding lower extremities of these 105 chains are connected in any suitable manner to a band or ring 40 surrounding the valve adjacent its lower end. Manifestly, as the unit including the valve 19 and the receptacle 21 is vibrated within the housing 10, the 110 chains 38 strike the lower conical portion 13 of the housing, and thereby separate and loosen the soot therefrom, so that the soot can be returned to the chimney 11 incident to the opening of the valve 19, which of 115 course takes place while the unit above defined is being vibrated.

55 While it is believed that from the foregoing description the nature and advantages of the invention will be readily apparent, we 120 desire to have it understood that we do not limit ourselves to what is herein illustrated and described, and that such changes may be resorted to when desired as fall within the scope of what is claimed.

60 What we claim as new is:

65 1. A soot extractor of the character described, comprising a soot collecting housing open at both ends and including frusto-conical upper and lower portions, means for 130

supporting the housing above a chimney, a conical-shaped cap supported by said means above the housing in spaced relation thereto, a bottomless receptacle-like baffle movable
5 within the housing, a normally seated hollow tubular valve supported by said baffle, and partly received by the latter, whereby the smoke and gases emitted from the chimney are caused to pursue a circuitous course
10 through the housing, and thereby separate the soot therefrom, said valve controlling communication between the housing and chimney, and adapted to be opened to permit return of the soot from the housing to
15 the chimney, and means for vibrating said baffle and valve as a unit within the housing, incident to the opening of the valve for the purposes specified.

2. A soot extractor of the character described, comprising a soot collecting housing open at both ends and adapted to be supported above a chimney, means arranged within the housing for separating the soot from the smoke and gases passing therethrough, said means including a normally seated hollow valve controlling communication between the housing and chimney, and adapted to be open to permit return of the soot from the housing to the chimney, means
25 for vibrating said soot separating means to loosen the soot therefrom and from the walls of said housing, and flexible elements carried by the valve for striking the bottom of the housing and loosening the soot therefrom incident to the vibration of said soot separating means.

In testimony whereof we affix our signatures.

WILLIAM H. WERNER.
CARL NEUMANN.
